UNITED STATES PATENT OFFICE.

LEWIS E. CURTIS, OF WARREN, OHIO, ASSIGNOR TO THE YOUNGSTOWN PRESSED STEEL COMPANY, OF WARREN, OHIO, A CORPORATION OF OHIO.

CORNER BEAD.

Application filed May 25, 1921. Serial No. 472,569.

To all whom it may concern:

Be it known that I, LEWIS E. CURTIS, a citizen of the United States, and a resident of Warren, in the county of Trumbull and State of Ohio, have invented certain new and useful Improvements in Corner Beads, of which the following is a specification.

My present invention relates to corner beads such as are used by plasterers to protect angles of plastered walls, and aims to provide a construction which will be simple and economical in manufacture, which will have a strong and well braced corner bead and in which ample provision will be made for the keying of the plaster.

The invention includes the novel features of construction and arrangement of parts hereinafter described and particularly defined by the appended claims.

My invention is illustrated in the accompanying drawing, in which:

Figure 1 is a perspective view of my improved corner strip.

Fig. 2 is a transverse sectional view showing the same as embodied in a plastered wall angle.

Fig. 3 is a side view.

Fig. 4 is a section on line 4—4 of Fig. 3. Referring by reference characters to this drawing, my corner strip is shown as comprising a corner bead 1 preferably of rounded formation carried by the narrow web portions 2 from the supporting sheets

3, the whole being formed by stamping or pressing from a single sheet of metal. The portions 2 are brought into proximity or contact with each other, the diameter of the head and the width of these portions 2 corresponding to the thickness of the plaster.

The supporting sheets or wings 3 are provided with openings 4 for the passage of nails 5 designed to secure the corner strip to the woodwork, as illustrated in Fig. 2.

In order to brace the corner bead and also provide for effectively keying the plaster

adjacent to the bead, raised bridge pieces 6 are arranged, extending preferably from the base of the bead to suitable points in the supporting sheets, and these bridge pieces are formed integral by slitting the sheet metal of which the corner strip is made on parallel lines and striking up the portion of the metal lying between the slits as clearly shown in the drawings. The raised bridge pieces provide spaces beneath them into which the plaster, shown at 7 in Fig. 2, passes, forming an effective key.

Such a strip as above described would be very readily and economically manufactured by the use of dies for stamping or pressing the sheet metal into the desired shape.

Having thus described my invention what I claim is:

1. A plasterer's corner strip having in combination, a corner bead, support elements, diverging attaching elements and bracing members extending from the bead, above the junction of the supporting elements and attaching elements, to the attaching elements remote from said junction and out of the plane of said member. 65 70

2. A plasterer's corner strip having in combination, a corner bead member, web members connecting the bead and diverging attaching members and bracing members, connecting the bead and attaching members and disposed out of the plane of the attaching members. 75

3. A plasterer's corner strip comprising a tubular bead and diverging supporting sheets connected thereto by adjacent web portions, the whole being formed of a single sheet of metal, portions of the sheets and webs being slit along parallel lines with portions of the metal between such slits pressed upward from the planes of the sheets. 80 85

In testimony whereof, I affix my signature.

LEWIS E. CURTIS.
